DISPENSING DEVICE

Clarence M. Smith, Cleveland, Ohio

Application November 2, 1931, Serial No. 572,507

4 Claims. (Cl. 299—83)

This invention relates to a dispensing device, and is particularly applicable to the dispensing of liquid soap and the like.

An object of the invention is to provide an improved dispensing device which will deliver a quantity of liquid into which has been interjected a quantity of gas.

Another object of the invention is to provide an improved dispensing device which will deliver intimately mixed predetermined quantities of liquid and gas.

Another object of the invention is to provide an improved dispensing device which will be simple in construction and operation.

Another object is to provide an improved dispensing device which will be composed of few and simple parts.

Other objects will hereinafter appear.

The invention will be better understood from the description of one practical embodiment thereof illustrated in the accompanying drawing, in which:

Figure 1 is a side elevational view, partly in section, of one embodiment of the invention applied to a wash basin;

Figure 2 is an enlarged central sectional view of the device of Figure 1;

Figure 3 is a cross-sectional view taken on the line III—III of Figure 2;

Figure 4 is a fragmentary view taken on the line IV—IV of Figure 3 and showing the parts in discharging position; and

Figure 5 is a perspective view of a series of washer-like members shown in the other figures.

In Figure 1, a basin of the conventional type is shown at 1, being provided with a faucet 2 and a drain 3 and supported upon a wall 4. Positioned above the wash basin is a tank 5 also secured to the wall and having an outlet pipe 6 upon which is attached the dispensing device indicated generally at D.

The dispensing device is better illustrated in Figures 2 to 5 and consists of a supporting bushing 7 threaded onto the end of pipe 6. Secured to the exterior of the bushing as by threads 8 is a cylindrical body or housing 9, and clamped between a shoulder 10 formed within this housing and the end of the bushing 7 are a plurality of disc-like members 11, 12, 13, 14, 15, 16, and 17 which will be hereinafter described in greater detail.

A hollow cylindrical plunger 18 is adapted to be reciprocated within the cylindrical housing 9 and its inner open end is provided with a packing ring or washer 19 conveniently of leather or the

like, secured to the plunger by a threaded clamping ring 20, so that a tight seal is effected between the plunger and casing. The outer end of the plunger is closed, with the exception of a central perforation or orifice 21 which serves as a vent during part of the operation, and during another part is closed, as will be described.

Supported by discs 11 to 16 is a cylinder 22 having a shoulder abutting the outer side of the disc 11 and a reduced cylindrical portion through 10 the discs.

Threaded upon the exterior of this end is a cup-like closure 23, the end of which bears upon the side of disc 16, so that the discs are compressed between this end and the shoulder of cylinder 22. This member is slotted as indicated at 24 to permit the ingress of fluid from pipe 6.

A slide valve 25 is arranged to reciprocate within the end of cylinder 22 and is prevented from moving completely into the cylinder by 20 locking ring 26. Passing through the valve is a central opening 27. A ball 28 is carried within the valve and seats upon a shoulder connecting the inner narrow portion of opening 27 and the outer widened portion thereof. Between the 25 widened portion and urging the ball upon its seat is a spring 29 secured by a washer 30 which, in turn is retained within the valve by the pinning over of the end of the latter.

A piston 31 is arranged to reciprocate within cylinder 22 and is secured by a screw 32 to an actuating rod 33. The end of the rod is substantially conical in shape as indicated at 34 and positioned to close the opening 21 in plunger 18. The rod is notched as indicated at 35, and this 35 notch receives a portion of a washer 36 which is expanded into the interior of plunger 18 adjacent its outer end so that the rod is free for slight longitudinal movement relative the plunger, this movement being sufficient to open and close opening 21 and permit the venting of the space between plunger 18 and the casing 9.

A spring 37 is positioned between parts 11 and 36 to return the plunger to its outermost position after it has been actuated; and a second 45 spring 38 is provided for moving the valve 25 to its outermost position with the locking ring 26 bearing upon the end of cylinder 22.

The washers 11 to 17 are as best illustrated in Figure 5, from which it will be noted that each washer except 17 has a central perforation large enough to permit the passage of the reduced end of cylinder 22, the last, 17, being a narrow ring pressing upon the adjacent washer 16 and clearing parts 22 and 23.

The end washers 11 and 16 are similar in that they extend continuously from about the reduced portion of cylinder 22 to the shell 9, but the former has a small perforation 39 permitting air to 5 pass from within casing 9 through the washer.

Washers 12 and 15 are identical, each being circular in shape and extending from cylinder 22 to casing 9, excepting at their bottoms, where notches 40 are provided. Each of these washers 10 is provided with two circular perforations 41 and 42, the former of which is in alignment and substantially coaxial with perforation 39, so that air passing through the last mentioned perforation will enter at the center of aperture 41. 15 Washer 13 has a notch 43 corresponding to notches 40 and apertures 44 and 45 in alignment with apertures 41 and 42. However, a passage 46 connects the central opening with aperture 44, and a second passage 47 connects apertures 20 44 and 45. From the latter aperture, the periphery of the disc is cut away throughout substantially 270°, until it reaches one side of notch 43, so that a passage 51 as shown in Figure 3 passing upwardly in a counter-clockwise direction 25 and around to the notch at the bottom is provided.

Washer 14 is substantially identical to washer 13 excepting that the passage 46 is omitted.

The washers are arranged as shown in Figure 30 5 and then placed tightly against each other, a small helical spring 48 fitting within the space formed by apertures 41, 44, 44', and 41, and a similar spring 49 fitting within that formed by apertures 42, 45, 45', and 42, so that the springs 35 constitute in effect screens through which the material must pass, the screens serving to agitate the fluid in its passage, and, due to their resiliency, permitting some lateral movement, to allow the passage of any solid particles present.

40 An aperture 50 is provided through cylinder 22 and positioned to communicate with slot 46.

The operation of the device is as follows:

Starting with the parts in the positions shown 45 in Figure 2, the pressure of the liquid soap or the like unseats ball 28 and permits this liquid to fill the space within the cylinder 22. As soon as this space has been filled, spring 29 causes the ball to reseat and the device is ready for actuation.

50 The operator presses the plunger 18 in, and during the time when it moves from its full line position to its dotted line position this plunger moves independently. However, when it reaches the dotted line position of Figure 2, aperture 21 is seated upon the conical end 34 of rod 33, and thereafter plunger and piston 31 move in unison. As these are moved inwardly, air is compressed within shell 9, and simultaneously the liquid within cylinder 22 is compressed, causing 55 liquid within cylinder 22 to move inwardly into the position shown in Figure 4 while it uncovers port 50.

60 The compressed air escapes through vent 39 into the interior of spring 48 and the liquid is forced through aperture 50 and through slot 46 into the interior of this same spring.

65 The streams of liquid and air enter substantially at right angles and, the liquid passing through the narrow slots of spring 48 is divided. 70 The interaction of the two streams causes them to be intimately mixed, churning soap and air into a series of bubbles and producing a thick lather. This action is, to an extent, repeated and augmented by passing through spring 49, and after the material has passed this far, it

circulates around the passage 51 between washers 12 and 15 and shell 9 to notches 40, 43, and 43' which are in alignment with a discharge opening 52.

The lather produced is very effective in washing, considerably greater in bulk than would be the soap of which it is composed, and prevents the wastage of said soap, as is common in devices which dispense soap in its liquid form. 5

10 While I have described the illustrated embodiment of my invention in some particularity, obviously many other embodiments will readily occur to those skilled in this art, and I, therefore, do not limit myself to the precise details 15 shown and described, but claim as my invention all embodiments, variations and modifications coming within the scope of the appended claims.

I claim:

1. A foam or lather producing device comprising two concentric cylinders, pistons arranged 20 to reciprocate in said cylinders, connections between said pistons whereby they may be simultaneously moved, a liquid supply line connected to one of said cylinders, a slide valve in said cylinder having a passage therethrough interposed in the path of liquid passing from the supply line to the cylinder, a check valve controlling said passage to admit liquid to said cylinder, a port from said cylinder arranged to be covered by said slide valve in the position which the parts 30 occupy when the device is not being actuated and exposed when said valve is actuated upon motion of said pistons from their normal position, a chamber with which said port communicates, a second discharge port between the other 35 cylinder and said chamber, and a discharge passage from said chamber to the exterior of the device.

2. A foam or lather producing device comprising two concentric cylinders, pistons arranged 40 to reciprocate in said cylinders, connections between said pistons whereby they may be simultaneously moved, a liquid supply line connected to one of said cylinders, a slide valve in said cylinder having a passage therethrough interposed in the path of liquid passing from the supply line to the cylinder, a check valve controlling said passage to admit liquid to said cylinder, a port from said cylinder arranged to be covered by said slide valve in the position which the parts 45 occupy when the device is not being actuated and exposed when said valve is actuated upon motion of said pistons from their normal position, a chamber with which said port communicates, a second discharge port between the other 50 cylinder and said chamber, a discharge passage from said chamber to the exterior of the device, and a resilient screen in said chamber.

3. A foam or lather producing device comprising two concentric cylinders, pistons arranged 60 to reciprocate in said cylinders, connections between said pistons whereby they may be simultaneously moved, a liquid supply line connected to one of said cylinders, a slide valve in said cylinder having a passage therethrough interposed in the path of liquid passing from the supply line to the cylinder, a check valve controlling said passage to admit liquid to said cylinder, a port from said cylinder arranged to be covered by said slide valve in the position which the parts 65 occupy when the device is not being actuated and exposed when said valve is actuated upon motion of said pistons from their normal position, a chamber with which said port communicates, a 70

second discharge port between the other cylinder and said chamber, a discharge passage from said chamber to the exterior of the device, and a plurality of resilient screens in said chamber and passage.

4. A foam or lather producing device comprising a bushing adapted to be secured to the end of a liquid supply line, a generally cylindrical casing secured to said bushing, a plurality of centrally apertured disc-like members clamped between said bushing and casing and provided with apertures to form two circular chambers communicating with each other, said chambers having three ports, one communicating with the interior of the casing, the second a radially inwardly extending port, and the third a discharge port to the exterior of the casing, a cylinder supported by said disc-like members concentric

with the casing, a port through said cylinder communicating with said radially disposed port, a slide valve in said cylinder having a passage in alignment with the passage through the bushing, a check valve controlling said passage to admit liquid to said cylinder, said slide valve being arranged to control the port through said cylinder, resilient means urging said slide valve to position covering said port, a plunger fitting within the casing, a second plunger fitting with in the cylinder, a port through the end of the first mentioned plunger, a rod connected to said second mentioned plunger and having an end arranged to close said last mentioned port when the plungers are moved inwardly, and a spring moving said plungers to their outermost position.

CLARENCE M. SMITH.
